US00D578067S

(12) **United States Design Patent**
Chen et al.

(10) **Patent No.:** US D578,067 S
(45) **Date of Patent:** ** Oct. 7, 2008

(54) **FILTER**

(75) Inventors: **Yu-Zheng Chen**, Taoyuan Hsien (TW);
Ching-Man Kao, Taoyuan Hsien (TW);
Shih-Hua Sheng, Taoyuan Hsien (TW)

(73) Assignee: **Delta Electronics, Inc.** (TW)

(**) Term: **14 Years**

(21) Appl. No.: **29/267,320**

(22) Filed: **Oct. 12, 2006**

(51) LOC (8) Cl. **13-03**

(52) U.S. Cl. **D13/147**; D13/123
